POLISHING MACHINE FOR IMPELLER WHEELS

Henry C. Stieglitz, Cleveland, Ohio, assignor to
Thompson Products, Inc., Cleveland, Ohio, a
corporation of Ohio

Application March 18, 1948, Serial No. 15,536

11 Claims. (Cl. 51—135)

1

This invention relates to a polishing machine, and particularly to a machine for rapidly and economically effecting the polishing of complex arcuate surfaces on a workpiece, such as the surfaces of an impeller vane.

As will be recognized by those skilled in this art, the surfaces of the vanes of an impeller wheel are of relatively complex configuration, for the most part having in cross-sectional contour an arcuate configuration wherein the radius of curvature of successive portions of the contour varies substantially. Heretofore, the quantity production of impeller wheels has been substantially impaired by virtue of the fact that the polishing of the vane surfaces could only be satisfactorily accomplished manually. Such manual operations not only greatly increased the time and cost of production, but had the further disadvantage of being dependent in a large extent upon the skill of the particular operator, and hence being subject to wide variations in the quality and uniformity of surface finish obtained.

Accordingly, it is an object of this invention to provide an improved polishing machine for complex arcuate surfaces of a workpiece, and particularly a machine that will rapidly, economically and uniformly effect the polishing of the vane surfaces of an impeller wheel.

A particular object of this invention is to provide a polishing machine wherein a moving abrasive belt is caused to be trained over the vane surface of an impeller wheel to polish the same, and wherein the impeller wheel is indexably carried on a platform movable transversely with respect to the belt so that the successive vanes thereof may be readily withdrawn from contact with the belt and the next vane moved into position to be contacted by the belt.

Still another object of this invention is to provide an improved polishing machine for the vanes of an impeller wheel wherein a more uniform polishing effect may be produced upon the successive vane surfaces by training a traveling abrasive belt successively over each of the vane surfaces in substantially identical spatial relationship thereto.

Still another object of this invention is to provide an improved belt lifter mechanism for an endless abrasive belt by which the belt may be manually shifted to an inoperative position with respect to the workpiece to permit the withdrawal of the workpiece and the reinsertion of the next workpiece in position to be contacted by the belt.

The specific nature of this invention, as well as other objects and advantages thereof, will be

2

come apparent to those skilled in the art from the following detailed description of the annexed sheets of drawings which, by way of preferred example only, illustrate one specific embodiment of the invention.

On the drawing:

Figure 1 is a side elevational view of a polishing machine embodying this invention, showing the polishing position of an impeller workpiece in dotted lines;

Figure 2 is a plan view of the machine of Figure 1;

Figure 3 is a partial plan view, illustrating the position of the work supporting carriage when the workpiece is withdrawn from the polishing position;

Figure 4 is an enlarged scale sectional view taken on the plane IV—IV of Figure 3; and

Figure 5 is an enlarged scale sectional view taken on the plane V—V of Figure 2.

As shown on the drawing:

The various elements of the machine embodying this invention may be conveniently mounted upon a stand 10 formed by welded assemblage of structural steel members and providing a flat table or base portion 10a with depending side flanges 10b and 10c, respectively, along opposed longitudinal edges. A table extension unit 11 is rigidly secured to side flange 10c of the table top 10a and provides support for a pair of spaced, upstanding bearing brackets 12. A similar pair of bearing brackets 13 are mounted on the opposite side flange 10b of the table top 10a and are respectively aligned with the bearing brackets 12. Each pair of opposed bearing brackets 12 and 13 supports a slide rod 14 which extends transversely across the table top 10a in overlying relationship thereto.

A work supporting platform or slide 15 is provided having a plurality of depending bearing members 16 rigidly secured thereto as by bolts 16a by which the slide 15 is slidably supported on the rod 14 for transverse movement across the top of table 10a. Slide 15 is provided on its top surface with an upstanding hub portion 17 which is suitably dimensioned so as to mount an impeller wheel W thereon for indexing movement about the axis of the wheel. The term "impeller" is used herein in a generic sense to define any element having circumferentially spaced fluid guide vanes. When the slide 15 is in its polishing position, illustrated in Figure 2, one or more vane elements V of the impeller wheel W overhangs the right hand edge (bottom of Figure 2) of the base 10a. When the slide 15 is shifted to its loading

and indexing position, as shown in Figure 3, then the vanes V of the impeller wheel W do not project over the right hand edge of the base 10a.

In accordance with this invention, an endless abrasive belt 20 is supported for peripheral movement adjacent the right hand edge of the base 10a so as to contact one of the vanes V of the impeller wheel W when the work supporting slide 15 is shifted to its polishing position. The belt 20 is supported in extended relationship, with its abrasive surface on the inside, by a plurality of pulleys, respectively a pulley 21 and pulley 23. Pulley 21 is the driving pulley, being keyed to the shaft 22a of a suitable motor 22 which in turn is secured by bolts 22b in depending relationship to a support plate 10d. The support plate 10d is secured in depending relationship to the table top 10a by a plurality of mounting bolts 10e. Pulley 23 is journaled on the end of a support arm 24, which in turn is mounted on an upstanding angle bracket 25 secured to the top of table 10a. To conveniently adjust the peripheral path of the endless abrasive belt 20, the position of pulley 23 may be adjusted over a wide range by varying the angular position of the support arm 24 with respect to the angle brackets 25. This is accomplished by securing support arm 24 to angle bracket 25 by a bolt 26 and nut 27 which passes through a suitable hole in support arm 24 and through an elongated vertical slot 25a formed in the angle bracket 25.

To tension the belt 20 during polishing operation, as well as to provide sufficient slack in the belt to permit the belt to be raised from the work surface, as will be later described, a belt tightening pulley 28 is provided which is journaled on the end of an arm 29 which has its other end pivotally mounted on a pin 30a supported in a depending bracket 30 secured to the table portion 10a. A tension spring 31 operates between the arm 29 and a fixed portion of the table to resiliently urge the belt tightening pulley 29 in the direction to effect a tightening of the belt 20.

With the construction thus far described, it is apparent that the various vanes V of an impeller workpiece W may be successively polished by the simple expedient of moving the slide 15 to its polishing position as illustrated in Figures 1 and 2 of the drawing wherein one of the vanes V will project into the path of and be engaged by the endless abrasive belt 20. After the polishing operation on such vane is completed, the slide 15 is moved laterally to its loading and indexing position, as illustrated in Figure 3, where the vanes are free of the belt 20, and the impeller wheel W is angularly indexed a distance corresponding to the angular spacing of the vanes V and the polishing operation repeated upon the next vane. However, it should be readily apparent that there would be an excessive abrading action produced upon the peripheral edge of any vane being polished, due to the initial picking up of the endless belt 20 upon the vane and the release of the belt 20 from the vane, when engagement or disengagement of the belt is accomplished solely by the lateral movements of the work supporting slide 15.

This undesirable effect is overcome in accordance with this invention by providing a belt lifting mechanism comprising a pair of rollers 35 journaled in spaced relationship on a support link 36. The rollers 35 are sufficiently spaced so as to engage the endless belt 20 at points respectively ahead of and behind the position of a vane V upon which the polishing operation is being

performed. The end of link 36 is pivotally mounted on a pin 38 suitably journaled in a bushing 37 rigidly secured to the table side flange 10c. An operating handle 39 is also journaled on the pin 38 and is rigidly secured to the link 36 as by welding. Hence, manipulation of the handle 39 will effect a shifting of the rollers 35 from their inactive position shown in solid lines in Figure 1, to their dotted line belt raising position, and it is apparent that in this latter position the belt 20 will be raised out of engagement with the vane V being polished. Of course, the additional extension of the belt 20 required to permit such raising is provided by a shifting of the belt tightening roller 28 against the bias of the spring 31.

Since the belt 20 should be maintained in its raised position relative to the vanes V of the workpiece during both the operations of retracting a polished vane from the polishing position and reinserting an unpolished vane, this invention provides a manually operable locking mechanism 40 for releasably retaining the belt raising mechanism in its non-polishing or raised position.

The latching mechanism 40 is best shown in Figure 5 and comprises a latching bar or slide 41 which is slidably journaled on the top of a block 42 which is suitably secured as by welding to the table side flange 10c. The slide 41 overlies a recess 42a formed in bracket 42 and such recess is employed to accommodate a spring 43, which operates against the bottom end of a vertical pin 44 which projects through a suitable aperture in the slide bar 41. A cover plate 45 is provided to guide the sliding movements of the slide bar 41 and such plate is provided with an elongated slot 45a through which the top portion of the pin 44 projects. The length of the slot 45a thus determines the extent of travel of the pin 44, and hence of the slide bar 41.

The end of slide bar 41 projects into the path of the handle member 39 of the belt shifting mechanism and has a cam surface 41a formed thereon to permit the handle member to immediately cam the slide bar 41 out of its path when such member is being shifted to its belt raising position. Having once passed the slide bar 41, it snaps into overlying engagement with the top surface of the handle 39 and hence prevents the return of handle 39 to its inactive or polishing position. The belt shifting mechanism will thus be held in its belt raised or non-polishing position until the slide bar 41 is manually released by pushing the pin 44 to retract the slide bar 41 from the path of the handle 39. Having once latched the handle 39 in its non-polishing position, the operator can proceed with a great deal of freedom in shifting the slide 15 and indexing the workpiece W thereon without any substantial danger of inadvertently contacting the vane surfaces with the traveling abrasive belt 20.

If desired, to facilitate the indexing operation, an indexing positioning device 50 may be provided. As is best shown in Figure 4, such device comprises a plunger 51 which is horizontally slidable in a suitable housing formed by the bolted assembly of two housing half parts 52 and 53, respectively. Half part 52 defines a recess 52a within which is mounted a spring 54. Spring 54 operates against the bottom end of a vertical pin 55 which is mounted in a suitable aperture in the plunger 51 and projects upwardly through an elongated slot 53a formed in the top housing part 53. The plunger 51 is of sufficient

length to project into the path of the vanes V of impeller wheel W when such plunger is in its extended position, as shown in Figure 4. To reduce the possibility of marring the vanes V of the impeller wheel W, a contact button 56 of relatively soft material may be mounted in the end of plunger 51 and secured therein by a set screw 57.

In its normal position, the plunger 51 projects in between two adjacent vanes V of the impeller W and hence functions to angularly index the impeller W with respect to the slide support 15. To shift the impeller W about its support post 17, the pin 55 is manually grasped and moved radially outwardly relative to the impeller to retract the plunger 51 from its position intermediate the vanes, whereupon the impeller may be freely rotated an angular distance corresponding to the separation of vanes, whereupon the pin 55 is released and the plunger 51 moved back to its indexing relationship with respect to the next impeller vane.

The weight of the belt lifting mechanism is suitably proportioned so that when the handle 39 is manually released, the entire mechanism will tend to pivot in a clockwise direction, as viewed in Figure 1, to assume a position out of engagement with the traveling belt 20. The gravitational movement of the belt lifting mechanism is arrested in such inoperative position by engagement of a depending L-shaped stop bracket 39a which is secured to medial portion of the handle 39 and engages a rigid projecting pin 43 mounted on the side of the bracket which supports the latch mechanism.

From the foregoing description, it is apparent that a polishing machine embodying this invention permits the polishing of the main surface of an impeller wheel to be accomplished rapidly, economically and accurately. In particular, with such a machine, there is no danger of the polishing belt being inadvertently engaged with finished surface portions of the impeller wheel workpiece so as to mar or gouge such. Furthermore, a very uniform degree of polishing can be produced upon each of the various vane surfaces of the impeller wheel and the tendency of the traveling belt to round off the peripheral edges of such vanes is substantially eliminated by the incorporation of the belt lifting mechanism.

It will, of course, be understood that various details in construction may be modified through a wide range without departing from the principles of this invention and it is, therefore, not the purpose to limit the patent granted hereon otherwise than necessitated by the scope of the appended claims.

I claim as my invention:

1. Machine for successively polishing circumferentially spaced surfaces on a workpiece having an opening therethrough, comprising an endless abrasive belt, a plurality of fixed pulleys supporting said belt in extended relation, power means for driving one of said pulleys, a carriage having an upstanding hub member, said workpiece being positioned on said carriage with the hub extending through the workpiece opening and providing a pivot axis for rotational indexing movements, means engaging said workpiece for locking said workpiece against rotation during the polishing movement of said belt, said carriage and said belt being relatively movable between remote positions and fixed polishing positions wherein said belt contacts one of said surfaces of the workpiece, and a belt shifting mecha-

nism selectively engageable with said belt to shift the belt out of engagement with the workpiece to permit unimpeded relative movements between said belt and carriage.

2. Machine for successively polishing circumferentially spaced, radially extending surfaces on a workpiece having an opening therethrough, comprising an endless abrasive belt, a plurality of fixed pulleys supporting said belt in extended relation, power means for driving one of said pulleys, a spring pressed movable pulley engaging said belt to tighten the same, a carriage having an upstanding hub member, said workpiece being positioned on said carriage with the hub member extending through the workpiece opening and providing a pivot axis for indexing movements about the workpiece axis, lock means engaging said workpiece for locking said workpiece against rotation during polishing movement of the belt means supporting said carriage for movement transverse to the path of said belt between positions remote and proximate to said belt, thereby permitting a selected arcuate surface of the workpiece to be immovably positioned in the path of said belt, and manually operable means for shifting said belt to selectively move said belt out of contact with the positioned workpiece, thereby permitting movement of said carriage to and from said polishing position without interference with said belt.

3. Machine for polishing the vanes of an impeller wheel having an axial opening comprising an endless abrasive belt, pulley means for driving and supporting said belt in open, extended relationship, a platform movable transversely with respect to said belt to and from a polishing position adjacent the belt, an upstanding hub on said platform extending through said axial opening for supporting an impeller wheel for free rotary adjusting movement about its axis, thereby successively positioning the vanes thereof in fixed position for engagement by said belt when said platform is shifted to said polishing position, an arm pivotally mounted adjacent said belt, a pair of rollers mounted on said arm, said rollers being constructed and arranged to respectively engage portions of said belt ahead of and behind the polishing position of a positioned impeller vane, and manual means for shifting said arm to raise said belt out of contact with the fixedly positioned impeller vane.

4. Machine for successively polishing circumferentially spaced, complex arcuate surfaces on a workpiece having an axial opening, comprising an endless abrasive belt, a plurality of fixed pulleys supporting said belt in extended relation, power means for driving one of said pulleys, a carriage movable relative to said belt, a centering member on said carriage disposed in said axial opening for supporting the workpiece for free rotational indexing movements about the workpiece axis, said carriage being movable relative to said belt between a remote position and a fixed polishing position wherein said belt contacts one of said arcuate surfaces of the workpiece, a belt shifting mechanism engageable with said belt to shift the belt out of engagement with the workpiece to permit unimpeded relative movements between said belt and carriage, and means for releasably latching said belt shifting mechanism in its belt shifted position.

5. Machine for polishing the vanes of an impeller wheel having an axial opening comprising an endless abrasive belt, pulley means for driving and supporting said belt in open, extended

relationship, a platform movable transversely with respect to said belt to and from a polishing position adjacent the belt, a centering member on said platform engaging in said axial opening for supporting an impeller wheel for free rotary indexing movement about its axis, thereby successively positioning the vanes thereof in fixed position for engagement by said belt when said platform is shifted to said polishing position, an arm pivotally mounted adjacent said belt, a pair of rollers mounted on said arm, said rollers being constructed and arranged to respectively engage portions of said belt ahead of and behind the polishing position of any positioned impeller vane, manual means for shifting said arm to raise said belt out of contact with the positioned impeller vane, and means for releasably latching said arm in its belt raising position.

6. Machine for polishing the vanes of an impeller wheel having an axial opening comprising an endless abrasive belt, pulley means for driving and supporting said belt in open, extended relationship, a movable belt tightening pulley, resilient means urging said belt tightening pulley in the direction to tighten said belt, a platform movable transversely with respect to said belt to and from a fixed polishing position adjacent the belt, a centering member on said platform engaging in said axial opening for supporting an impeller wheel for free rotary indexing movement about its axis, thereby successively positioning the vanes thereof for engagement by said belt when said platform is shifted to said polishing position, an arm pivotally mounted adjacent said belt, a pair of rollers mounted on said arm, said rollers being constructed and arranged to respectively engage portions of said belt ahead of and behind the position of a positioned impeller vane, and manual means for shifting said arm to raise said belt out of contact with the positioned impeller vane.

7. A machine for polishing the vanes of an impeller wheel having an axial opening comprising a base, a pair of spaced slide rods extending laterally across said base, a platform slidably mounted on said slide rods, a hub on said platform for engaging in the axial opening of said wheel and supporting the wheel for free rotary indexing movements about the wheel axis, locking means engaging said workpiece in successive indexed positions and rigidly holding said workpiece whereby successive vanes may be rigidly positioned in overhanging relation to the edge of said base, an endless abrasive belt, a plurality of pulleys mounted on said base adjacent said edge for supporting said belt in an extended condition adjacent said edge of the base and abutting the surface of an overhanging vane, power means for driving one of said pulleys to peripherally move said belt, thereby polishing said vane surface, and a manually operable belt lifter mechanism having a pair of rollers engageable with said belt respectively on either side of the overhanging vane, said belt shifting mechanism being shiftable to a position wherein said belt is lifted off said vane surface.

8. A machine for polishing the vanes of an impeller wheel having an axial opening comprising a base, a pair of spaced slide rods extending laterally across said base, a platform slidably mounted on said slide rods, a vertical hub on said platform engaging in the axial opening of the impeller wheel and supporting the wheel for free rotary indexing movements about the wheel axis, whereby successive vanes of the impeller

may be positioned in overhanging relation to the edge of said base, an endless abrasive belt, a plurality of pulleys mounted on said base adjacent said edge for supporting said belt in an extended condition adjacent said edge of the base and abutting the surface of an overhanging vane, a movable belt tightening pulley engaging said belt, resilient means urging said pulley in a direction to tighten said belt, means for driving one of said pulleys to peripherally move said belt, thereby polishing said vane surface, a manually operable belt lifter mechanism having a pair of rollers engageable with said belt respectively on either side of the overhanging vane, said mechanism being shiftable to a position wherein said belt is lifted off said vane surface, and means for locking said belt lifting mechanism in its belt raising position.

9. A machine for polishing an impeller wheel having a central apertured hub and spaced vanes extending radially from the hub, comprising a base, a plurality of pulleys pivotally mounted on said base, a polishing belt disposed in a closed loop over said pulleys in a substantially vertical plane alongside the side face of said base, journals mounted on said base, a carriage having support rods slidably disposed in said journals for movement transversely of said base toward and away from said belt, an upstanding pivot hub on said carriage arranged to extend through the aperture of the wheel and guide it for free selective rotation about the axis of the hub, a bar slidably mounted on said base having an end portion movable to a position between adjacent blades on the wheel to prevent rotation of the wheel, spring means connected to one of said pivoted pulleys and arranged to urge the belt against a blade disposed inside the loop, and means acting against said spring means for moving said belt away from the workpiece prior to lateral movement of said carriage.

10. A machine for polishing the curved surface of a blade comprising a support structure, a carriage slidable on said structure, a pair of pulleys disposed for rotation adjacent said support structure, means for driving said pulleys, a belt disposed in a loop over said pulleys, means for locking a blade on said carriage in a position extending substantially normal to the plane of said pulleys, and means for spreading the loop of said belt, said carriage being movable on said support structure to position the blade inside said spread loop with the curved surface adjacent the belt.

11. A machine for polishing a workpiece having a central portion and spaced vanes radiating outwardly from the central portion, a carriage mounting the workpiece for rotation about its axis independently of movement of said carriage, an endless abrasive belt, a plurality of pulleys supporting said belt in extended relation, power means for driving one of said pulleys, said carriage and said belt being relatively movable between remote positions and fixed polishing positions wherein said belt contacts one of the vanes of the workpiece, and a belt shifting mechanism selectively engageable with said belt to shift the belt out of engagement with the workpiece prior to movement of said carriage to permit unimpeded relative movement between said belt and said vane.
